T. C. RUSSELL

HAIR STRAIGHTENING IRON

Filed March 30, 1925

Inventor:
Thomas C. Russell

by Brown, Boettcher & Ditmar,
Attnys.

UNITED STATES PATENT OFFICE.

THOMAS C. RUSSELL, OF CHICAGO, ILLINOIS.

HAIR-STRAIGHTENING IRON.

Application filed March 30, 1925. Serial No. 19,219.

To all whom it may concern:

Be it known that I, THOMAS C. RUSSELL, a citizen of the United States, residing at Chicago, in the county of Cook and State 5 of Illinois, have invented a certain new and useful Improvement in Hair-Straightening Irons, of which the following is a full, clear, concise, and exact description, reference being had to the accompanying drawings, 10 forming a part of this specification.

My invention relates to an improved hair straightening iron, particularly useful for taking kinks, waves or curls out of hair and leaving them straight. My improved device is clearly shown on the accompanying 15 drawing in which—

Figure 1 is a side elevational view;

Fig. 2 is a plan view of a part of the 20 operating members;

Fig. 3 is an enlarged sectional view on plane 3—3, Figure 1, and

Fig. 4 is a similar sectional view showing a different relative position of the parts.

The general construction and the appearance of the device is the same as that of the ordinary electric curling iron. It comprises a heating rod 10 extending from a grip or handle 11 which is strengthened by the ferrule 12. When the iron is electrically 25 heated the rod 10 is made tubular to receive the electric resistance element 13. Co-operating with the heating rod is the jaw structure *a*. This structure comprises the flat body part 14 having the bifurcated end 30 15 which receives the rod 10 and is pivoted by means of the pin 16 supported by the bracket 17 which is secured to the rod 10 adjacent ferrule 12. The end of the jaw structure has secured thereto the handle or 35 grip sleeve 18 alongside of the main grip 11. The jaw structure can then be readily swung to carry its body part 14 against or 40 away from the rod 10. Extending from the body part 14 at the sides thereof and substantially at right angles therewith are the 45 teeth 19 separated by the grooves 20, these teeth extending alongside of the rod 10 when the body part 14 is against the rod. To increase the contact area between the 50 rod and body part 14, the adjacent side of

the rod 10 may be flat as indicated at 21. In using the device, the jaw structure is swung to open position and the rod 10 is then slipped under the hair to be treated, as shown in Fig. 4. The jaw structure is 55 then closed and during such closure movement, the teeth 19 separate and spread the hair uniformly in the passageways 20, the distributed hair being then held down between the rod 10 and the flat blade part 14 60 of the jaw structure. As the hair is then clamped with more or less pressure, the device is moved laterally to draw it slowly along the hair, which, by its contact with the hot rod, will then be heated and straightened. Under some conditions, as where the hair is persistently curly or kinky, the hair 65 can first be treated with some materials, such as tallow, wax, composition, or other substances which, after heating, will stiffen 70 or harden. After such treatment, the device is applied to the hair as before described, the heat then melting or softening the dressing while the hair is being clamped and being stroked, and the dressing stiffening or hardening after it has cooled, and then retaining the hair in straight condition. To facilitate inserting the rod or jaw 75 blade under the hair, they are pointed at their ends as clearly shown on the drawing. 80

I claim as follows:—

1. A hair dressing device of the class described, comprising an elongated flat hair receiving member, hair distributing teeth along the sides of said member, and a heating member adapted to be applied to said hair receiving member between the teeth thereof. 85

2. In a hair dressing device of the class described, the combination of an elongated member having a flat hair receiving surface thereon and hair distributing teeth along the sides of said surface, and a heating rod having a flat surface adapted to be applied to said hair receiving member between the teeth thereof. 90

In witness whereof, I hereunto subscribe my name this 27th day of March, 1925.

THOMAS C. RUSSELL.
